A. G. CAMERON.
DRAWING INSTRUMENT,
APPLICATION FILED JULY 19, 1920.

Patented Dec. 12, 1922.

INVENTOR

A. G. Cameron

BY *John W. Cameron*

ATTS

UNITED STATES PATENT OFFICE.

ALEXANDER G. CAMERON, OF WINNIPEG, MANITOBA, CANADA.

DRAWING INSTRUMENT.

Application filed July 19, 1920. Serial No. 397,540.

To all whom it may concern:

Be it known that I, ALEXANDER G. CAMERON, of the city of Winnipeg, in the Province of Manitoba, Canada, have invented 5 certain new and useful Improvements in Drawing Instruments, of which the following is the specification.

The invention relates to improvements in drawing instruments and an object of the 10 invention is to provide a drawing instrument which can be used by draughtsmen, mechanics or such persons for quickly and accurately drawing regular or irregular, straight or curved lines or figures and which 15 is arranged so that it can be quickly and positively set and easily manipulated.

A further object is to provide an instrument whereby one can readily reproduce in a drawing an irregular curve, the instrument 20 being first applied to the curved surface, then fitted and set and afterwards utilized to draw the curve and provide the required reproduction.

A further object is to provide a light, 25 compact, easily assembled and simply constructed instrument which can be readily manufactured and sold at comparatively low cost.

A further object is to provide a drawing 30 instrument which can be readily enlarged or decreased in size to suit requirements.

With the above more important objects in view the invention consists essentially in the arrangement and construction of parts 35 hereinafter more particularly described and later pointed out in the appended claims, reference being had to the accompanying drawing in which:—

Fig. 1 is a plan view of the instrument. 40 Fig. 2 is an edge view thereof.

Fig. 3 is an enlarged detailed horizontal sectional view centrally through the joint formed between adjacent sections.

Fig. 4 is an enlarged detailed vertical 45 sectional view through the joint formed between the adjacent sections.

Fig. 5 is an enlarged detailed vertical sectional view through the block carried by the central section, the adjusting screw and 50 associated parts being shown in side elevation.

Fig. 6 is an enlarged detailed vertical sectional view at 6—6' Fig. 1.

Fig. 7 is a perspective view of the end 55 arm.

Fig. 8 is a perspective view of the set screw.

Fig. 9 is a plan view of the locking clamp.

Fig. 10 is a sectional view at 10—10' Fig. 9. 60

In the drawing like characters of reference indicate corresponding parts in the several figures.

The present instrument is shown as formed from three similar adjustable sections 1, 2 65 and 3, an end arm 4 and a flexible ruling bar 5. I wish here, however, to state that whilst three sections are shown any number of sections could be connected together in an instrument, this depending entirely on the 70 requirements.

The central section 2 is formed from an upper and lower pair of channel bars 6 and 7 of a predetermined length and having the flanges of the channel bars cut away at the 75 ends to provide extending end bearings 8 and 9. A block 10 is inserted centrally between the channel bars and is securely riveted to them as indicated at 11.

The end sections 1 and 3 are identically 80 constructed, these also being formed from channel bars of predetermined length and also having the flanges cut away at the ends. The outer ends of the channel bars of the sections 1 and 3 form bearings 12 whilst 85 the inner ends are cut away in a semi-circular manner as indicated at 13 to fit the semi-circular ends of the section 2.

In all the sections the flanges of the channel bars extend towards each other but are 90 spaced apart to provide side guides indicated at 14 which admit the adjusting screws hereinafter referred to.

The inner ends of the sections 1 and 3 are pivotally secured to the ends of the section 95 2 by means of pivot pins 15 and 16. The joint is made by securing as by riveting at 17 spaced extending end strips 18 to the inner ends of the sections 1 and 3 and having the pins 15 and 16 passing pivotally through 100 the extending ends of the strips 18. Spacing strips 19 are inserted between the spaced ends of the strips 18, the said strips 19 being really part of the central section and being pivotally mounted on the pivot pins 105 15 and 16.

This arrangement provides a particularly strong pivot joint between the sections. The outer ends of the sections 1 and 3 are plugged 110 between the bearings 12 by a filling plug 20

riveted as indicated at 21 to the section. The blocks are supplied with an exposed cross slot 22 and a set screw 23 is screw threaded into the block, the said set screw having flat 5 sides 24 at the slot. This set screw permits of the attaching to the outer end of either of the sections 1 and 3 the end arm 4 which presents a straight drawing edge 4'. One end of the end arm is adapted to enter 10 the slot 22 hereinbefore mentioned and it is fitted with a pivot opening 25 and an end slot 26 forming an entrance to the opening 25, the said slot being narrower than the diameter of the opening 25 and of a width 15 such that it will just nicely span the flat sides 24 of the screw.

According to this arrangement it will be apparent that the end arm 4 can be attached to either of the sections 1 or 3 by passing 20 the flat part of the screw through the slot 26 and into the opening 25. Afterwards one can swing the arm as desired, the screw acting as the pivot point and in this operation it is desirable to press in on the outer end 25 of the arm to prevent the flat part of the screw from escaping out of the slot 26.

The central section 2 of the instrument is fitted with an adjusting screw or spindle 27 which passes slidably through the block 10 30 and is fitted at opposite sides of the section with jam nuts 28 and 29. The sections 1 and 3 of the instrument are also each provided with a pair of adjusting screws or spindles 30 and 31 which pass through the slots 14, 35 being slidable therein and they are fitted each with a pair of jam nuts 32 and 33 at opposite sides of the sections. Obviously by manipulating the jam nuts 28 and 29 the central spindle 27 can be adjusted in or out 40 whilst by manipulating the nuts 32 and 33 the spindles 30 and 31 can not only be adjusted in and out but can also be adjusted endwise in respect to the sections 1 and 3. The flexible ruling bar 5 is connected pivotally as indicated at 34 to the inner ends of 45 the adjusting screws or spindles.

In order to permit one to positively hold the joints between the sections locked I will provide as part of the equipment of the instrument a number of locking clamps which are best shown in Figures 9 and 10, the 50 said clamps 35 being of a channel bar cross section and having the ends turned at a fixed angle.

With these clamps supplied one can place selected clamps over the joints between the sections and the flanges of the clamps engaging with the flanges of the bars of the sections will positively hold the sections 55 locked against turning.

From the above description it will be obvious that this instrument can be used for drawing either straight line figures, regular or irregular, or curved lines regular or 60 irregular, the straight line figures being

drawn by ruling on the inner edges of the sections, whilst the curved lines are drawn by ruling on the inner edge of the flexible bar 5.

In order to better understand the possibilities of this instrument I will explain how it can be used in a variety of ways.

In order to draw a straight line one simply releases the jam nuts 32 and 33 to allow the sections to swing until they are aligned and 75 the straight line can then be drawn either at the inner or outer edges of the sections.

To draw, say a regular hexagon, one would adjust the jam nuts to allow the end sections 1 and 3 to take a position at an 80 angle of sixty degrees to the section 2. One half of the hexagon can then be drawn and then by turning over the rule the other half can be drawn. Various other regular figures can obviously be drawn by properly 85 setting the sections and moving the said rule to complete the regular figure.

Where one desires to draw a curved surface he can do this by adjusting the screws 27, 30 and 31 to adjust the flexible ruling 90 bar and then set the jam nuts to hold it in a fixed position.

The flexible ruling bar arrangement is particularly useful where it is desired to reproduce the curvature of a fixed body for 95 making patterns and such like. As an example, supposing one wished to reproduce the curvature of the side of a boat, the back of an automobile or such like he would simply adjust the screws 27, 30 and 31 and 100 the jam nuts until he had fitted the flexible bar to the existing curved face and then lock the jam nuts when accurately fitted. The existing curve can then be reproduced in a drawing by drawing a pencil or such 105 like line along the inner side of the flexible bar.

Whilst I have described several manners of using this instrument, it will be readily understood that these are only explanatory 110 of and are in no way intended to limit the use of the instrument as obviously it can be set in a multiplicity of ways to accommodate the work in hand.

The bar 4 can be attached or detached 115 when desired and is readily a fitting to the instrument rather than an essential part of it.

What I claim as my invention is:—

1. In combination, a plurality of pivotally connected end and intermediate ruling sections, a flexible resilient ruling bar, a connection between the ruling bar and an intermediate section, said connection permitting of the adjustment of the flexible bar towards 120 and away from the said intermediate section and adjustable connections connecting the flexible bar to the end sections, said adjustable connections permitting of the adjustment of the flexible bar towards and away 125 130

from the said latter sections and the shifting endwise of the connections in respect to the said latter sections.

2. In combination, a central ruling section, end ruling sections pivotally attached to the ends of the central section, an adjusting screw passing through the central section, means for locking the screw in adjusted relation to the central section, a plurality of adjusting screws passing through the end sections and free to move towards and away from the ends of the said end sections, means for locking the said latter screws in any adjusted position in respect to the end sections and a flexible resilient ruling bar pivotally attached to the inner ends of the various screws.

3. In combination, a plurality of similar pivotally connected ruling sections comprising a central and end sections and with the end sections presenting lengthwise extending slots, an adjusting screw passing through the central section centrally and adjustable in a direction at right angles to the said central section, a plurality of adjusting screws passing through the slots in the end sections and movable endwise within the slots, means for adjusting the said latter

screws in a direction at right angles to the end sections and a flexible resilient ruling bar pivotally attached to the inner ends of all the screws.

4. In combination, a central section and end ruling sections pivotally connected to the central section, the said end sections presenting lengthwise extending slots and the said central section being fitted centrally of its length with a stationary block, a centrally positioned adjusting screw passing slidably through the block, jam nuts on the screw at opposite sides of the central section, a plurality of adjusting screws passing through the slots of the end sections and movable endwise within the slots, a pair of jam nuts mounted on each of the latter screws and engageable with the opposite sides of the end sections and a flexible resilient ruling bar connected pivotally to the inner ends of all the screws.

Signed at Winnipeg, Man. this 24 day of June 1920.

ALEXANDER G. CAMERON.

In the presence of:—

G. S. ROXBAUGH,
K. B. WAKEFIELD.
